UNITED STATES PATENT OFFICE.

FRANK WOODRUFF, OF ROCHESTER, PENNSYLVANIA, ASSIGNOR TO HENRY C. FRY, OF ROCHESTER, PENNSYLVANIA.

GRINDING GLASS TUMBLERS.

No. 905,486.

Specification of Letters Patent.

Patented Dec. 1, 1908.

Application filed January 27, 1908. Serial No. 412,717.

To all whom it may concern:

Be it known that I, FRANK WOODRUFF, a resident of Rochester, in the county of Beaver and State of Pennsylvania, have invented certain new and useful Improvements in Grinding Glass Tumblers, of which the following is a specification:

Thin glass tumblers—known in the trade as “punch” tumblers—are blown in bottle-like blanks which are capped off to form the tumbler mouth. This leaves a rough edge which must be ground off, and it is to the grinding of these edges that the present invention relates.

15 The primary object is to provide for the accomplishment of this grinding automatically by simply placing the tumblers in inverted position on a moving grinding surface. The tumblers are held from moving 20 with such surface, and may even be moved in an opposite direction, and the manipulation of the tumblers is preferably such that each one rotates on the grinding surface as the latter moves therebeneath, the result being that the edges are ground perfectly and 25 very rapidly and with little or no loss through breakage.

30 A further feature of the invention is the facility and rapidity with which the tumblers are handled by a single operator, also the capacity of the machine for grinding a large number of tumblers at one time.

In the accompanying drawings, Figure 1 is a vertical sectional view of the preferred 35 form of apparatus by which the invention is practiced and in which it is embodied, and Fig. 2 is a top plan view, half of the upper portion of the mechanism being broken away to illustrate the parts beneath. Fig. 3 is a 40 cross sectional view, enlarged, of one of the tumbler holding arms, taken on line 3—3 of Fig. 2. Fig. 4 is a detail view of one of the tumblers with a weight resting thereon.

45 Referring to the drawings, 2 designates a tubular post which may be cast integral with the drip receptacle 3 at the lower end thereof. Secured to the upper end of the post is the horizontal circular plate 4, and secured to and rising from this plate is the 50 circular head 5 of smaller diameter.

6 is the tumbler supporting and grinding disk which rotates on the ball bearing 7 on head 5, the disk being secured to the upper end of operating shaft 8 which, in the pres-

ent embodiment, is extended downwardly 55 through post 2 and provided with a driving pulley 9 beneath the floor. Obviously, the driving mechanism may be differently arranged.

Rotatable on plate 4 on ball bearing 10 60 is the ring-like plate 11, cogged on its inner periphery at 12, thus constituting the plate an internal gear. Secured to and radiating outward from the ring-like gear 11 are arms 13, having upward extensions 14 at their 65 outer ends which clear the outer edge of disk 6 and rise above the same.

15 are horizontal arms spaced slightly above the top surface of disk 6 with their outer ends secured to the upward arm-ex- 70 tensions 14, and with their inner ends secured to ring 16 similarly spaced above the grinding disk and concentric therewith. Disk 6 is preferably depressed or hollowed at its center, as indicated at 6', and this de- 75 pression and the ring form a receptacle for the pulverulent abrasive 17, with a water drip 18 arranged thereabove and adjusted to maintain the abrasive at the proper fluid or semi-fluid consistency. The rotation of 80 the grinding disk causes the abrasive to move outwardly over its top surface in the presence of the edges of tumblers A. The tendency of the abrasive is to work toward the periphery of the disk, discharging over 85 the edge thereof, and to confine and collect these drippings a funnel-like deflector 19 is secured to the arm extensions 14, and forms a raised rim 20 around the grinding disk but separated therefrom. The liquid abrasive 90 discharging over the edge of the disk is thus directed downward and inwardly so as to drain into receptacle 3. A depending guard 21 may be secured to gear 11 for preventing 95 the abrasive from reaching bearing 10.

The purpose of arms 15 is to prevent the tumblers from moving with the grinding disk, and the arrangement is preferably such that the arms are caused to rotate oppositely to the disk, though at lower speed. This is 100 accomplished by gearing interposed between shaft 8 and the internal gear 11, the gearing being here shown consisting of a pinion 22 on the shaft, with the large gear wheel 23 meshing therewith and journaled on plate 4, 105 while secured to wheel 23 is pinion 24 which meshes with the cogged surface 12 of gear 11. By this means said gear and the arms

supported thereby both below and above the grinding disk are rotated in a direction opposite to that in which the disk rotates. Each of arms 15 has its top and side faces 5 covered with wood strips 15' for engaging the tumblers without injuring them. A similar wood strip 25 is secured to the inner side of rim 20 between adjacent arms 15 for similarly engaging and protecting the tumblers.

10 In operation, the single operator of the machine takes his stand or station at any convenient point, say point S, and as each row of tumblers is moved in front of him, he simply removes the outermost tumbler of the 15 row and places a fresh tumbler at the inner end of the row without interrupting the continuous movement of the machine, the motion of grinding disk 6 causing the tumblers to rotate outwardly on the disk as far as possible, with the outermost tumbler of each 20 row engaging rim strip 25. By this means all the tumblers are subjected to the same amount of grinding action. There can be absolutely no confusion, and the work is perfectly uniform. For grinding tumblers not 25 heavy enough to bear on the grinding disk with sufficient pressure, a weight 26, preferably of lead, may be placed on each tumbler, as shown in Fig. 4.

30 It is characteristic of the operation that the motion of the grinding disk beneath the tumblers causes each tumbler to rotate on its edge, thus effecting a double or compound grinding movement. After the tumblers are 35 placed on the machine they require absolutely no attention on the part of the operator. The grinding disk is preferably formed of cast-iron with a smooth top surface and the abrasive may be any material suitable 40 for the purpose. As the sides of the tumblers have contact only with the wood faces of the strips there can be no breakage or injury to the glass such as would occur if the faces were of iron or other metal.

45 I claim:—

1. A tumbler grinding machine comprising horizontal arms, a grinder rotatable beneath the arms adapted to support rows of tumblers which bear against the arms with 50 the tumblers of each row bearing against each other, the motion of the support and the resistance of the arms operating to rotate each tumbler and work the rows of tumblers outwardly over the grinder, and stop means engaged by the outermost tumbler of each row.

2. A tumbler grinding machine comprising a series of horizontal radially disposed arms, a grinder rotatable beneath the arms 60 on an axis concentric therewith and adapted to support rows of tumblers—one row bearing against each arm and the tumblers of each row bearing against each other, the movement of the support and the resistance 65 of the arms operating to rotate each tumbler

and to work the rows of tumblers outwardly over the grinder, and stop means engaged by the outer tumbler of each row.

3. A tumbler grinding machine comprising a series of connected horizontal arms, a grinder beneath the rotatable arms adapted to support a separate row of tumblers bearing against one side of each arm and against each other and sustained by the grinder, the movement of the grinder and the resistance 75 of the arms operating to rotate each tumbler and to move the rows outwardly over the grinder, stop means engaged by the outer tumbler of each row, and mechanism for rotating the arms and the grinder in reverse 80 directions.

4. A tumbler grinding machine comprising a horizontal rotatable tumbler grinder, arms above the grinder and against which the tumblers bear and by which they are 85 held from moving with the grinder, and sustaining means beneath the grinder for said arms.

5. A tumbler grinding machine comprising a horizontal rotatable tumbler grinder, 90 a frame rotatable beneath the grinder in direction opposite to that in which the grinder rotates, and tumbler engaging arms carried by said frame above the grinder.

6. A tumbler grinding machine comprising a horizontal rotatable tumbler grinder, arms arranged radially beneath the grinder with upward extensions at their outer ends, and tumbler engaging means above the grinder and secured to said upward arm extensions. 100

7. A tumbler grinding machine comprising a horizontally rotatable tumbler grinder, a frame rotatable beneath the grinder, the frame having upturned extensions reaching 105 above the grinder, and tumbler engaging arms extending over the grinder and secured to said upturned extensions.

8. A tumbler grinding machine comprising a vertical rotatable shaft, a horizontal 110 tumbler grinder secured thereto, a fixed support beneath the grinder, a ring-like plate rotatable on the fixed support and geared to said shaft, and ware-engaging arms above the grinder with sustaining means extending thereto from the ring-like plate. 115

9. A tumbler grinding machine comprising a vertical rotatable shaft, a horizontal tumbler grinder secured thereto, a fixed support beneath the grinder, an internally 120 cogged ring-like plate rotatable on the fixed support with arms radiating outwardly therefrom, a pinion on the vertical shaft and connecting gearing interposed between said pinion and the internally cogged plate, and tumbler-engaging arms secured to said 125 radially arranged arms.

10. A tumbler grinding machine comprising a horizontally rotatable tumbler grinder, 130 a rim extending above and sustained free of

the grinder, and tumbler engaging arms extending over the top surface of grinder and also sustained free of the latter.

11. A tumbler grinding machine comprising a horizontally rotatable tumbler grinder, and a frame spaced above and sustained independently of the grinder, said frame having a central ring-like part for confining abrasive material, and ware-holding arms extending from the ring-like part outwardly over the grinder.

12. A tumbler grinding machine comprising a horizontal rotatable tumbler grinder having a central depression in its top face,

and a frame spaced above and sustained independently of the grinder, the frame having a central ring-like part extending around said top depression for confining abrasive material, and ware-holding arms extending from the ring-like part outwardly over the grinder.

In testimony whereof I affix my signature in presence of two witnesses.

FRANK WOODRUFF.
